POTATO DOUGH EXTRUDING MACHINE

David A. Farrant, Northridge, Calif., assignor to The
Scionics Corporation, a corporation of California

Filed July 25, 1969, Ser. No. 18,402

Term of patent 14 years

Int. Cl. D15—12

U.S. Cl. D55—1

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a front view of one form of the potato dough extruding machine showing my new design.

FIG. 2 is a view of one side.

FIG. 3 is a top view.

FIG. 4 is a rear view.

FIG. 5 is a view of the other side.

FIG. 6 is a bottom view.

FIG. 7 is a front view of a modified form of the design shown in FIG. 1.

FIG. 8 is a side view of one side.

FIG. 9 is a top view.

FIG. 10 is a rear view.

FIG. 11 is a view of the other side.

FIG. 12 is a bottom view.

I claim:

The ornamental design for a potato dough extruding machine, as shown and described.
